UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

METHOD OF AND APPARATUS FOR REMOVING MOISTURE FROM PAPER STOCK.

Application filed October 19, 1921. Serial No. 508,653.

To all whom it may concern:

Be it known that I, ANTON J. HAUG, a citizen of the United States, and a resident of Nashua, county of Hillsborough,

5 State of New Hampshire, have invented an Improvement in Methods of and Apparatus for Removing Moisture from Paper Stock, of which the following description, in connection with the accompanying drawings, is 10 a specification, like characters on the drawings representing like parts.

This invention relates to methods of and apparatus for removing moisture from paper stock and consists in improvements 15 which simplify the extraction of moisture from the pulp, whether the consistency of the latter is relatively thick or relatively thin, and which permit the extraction of any required amount of moisture from the 20 stock. It also consists in improvements whereby, without the use of felt, a web or fibre layer can be formed from stock where the fibres are held in liquid suspension.

The invention will be best understood by 25 reference to the following description when taken in connection with the accompanying illustration of one specific embodiment of the apparatus, while its scope will be more particularly pointed out in the appended claims.

In the drawings,—

Fig. 1 is a side elevation of an apparatus embodying one form of the invention;

30 Fig. 2 is a transverse cross-sectional elevation, diagrammatical in character, showing the relation of the expressing rolls in the apparatus of Fig. 1; and

Fig. 3 is a similar cross-sectional elevation showing a modified form of apparatus.

40 Referring to the drawings and more particularly to Figs. 1 and 2, the stock from which the moisture is to be removed is delivered to the upper surface of a hollow, perforated cylinder 5, which is driven from any suitable source of power in the direction of the arrow shown in Fig. 2. If the object is merely to extract moisture the stock may be applied from above to the upper surface of the cylinder in any desired way, as by providing a compartment or chamber to which the stock is delivered and of which the cylinder 5 and the cooper-

ating couch or expressing roll 7 form the bottom. If it is desired to form a web or sheet, however, the stock is preferably applied from above by delivering to the upper surface of the cylinder a measured, uniform stream capable of forming an even, uniform sheet on the foraminous surface of the cylinder as the latter revolves. In 55 the apparatus illustrated in Figs. 1 and 2, there is provided for this purpose a stock supply chamber 9 fed from the feed pipe 11 having a baffle plate 13, the stock passing out under the baffle plate and over the 60 weir plate 15, the height of latter and the rate of feed through the pipe being adjusted to give sheet of the require thickness.

The cylinder 5 has a foraminous surface and may be of the general construction 70 commonly utilized in cylinder molds, permitting ready drainage to its interior of the surplus or free moisture contained in the stock. The water passing to the interior of the cylinder passes to the bottom 75 of the interior thereof and thence through the perforations therein into the drip pan 17 or other receptacle, whence it escapes through any suitable waste pipe 19.

Cooperating with the foraminous cylinder 5 is the expressing roll 7 adapted to be pressed relatively toward the cylinder and express water from the stock as the latter passes between the perforated roll and the expressing roll, such expressed 85 water also passing to the interior of the hollow cylinder and to the drip pan 17.

Any suitable means may be employed for exerting the necessary pressure between the rolls, but herein the roll 7 is mounted in stationary journals 21, while the roll 5 is mounted at each end in journals 23, the latter being adapted to slide horizontally on guideways 25 supported on the main frame 27 and the necessary pressure between 90 the two rolls being maintained by the coiled spring 29, the compression of which may be adjusted through the hand-wheel 31.

The perforated cylinder which receives the stock in the first instance should preferably be constructed with an open mesh so as to permit the free passage of the surplus water through its walls, and such a form of cylinder is usually incapable of

withstanding excessive pressure. A relatively moderate pressure therefore only is maintained between the expressing roll 7 and the perforated cylinder 5, subsequent 5 expressing action or actions being relied upon to further extract moisture as may be required. The expressing roll 7 which is unperforated is preferably covered with felt or other soft, yielding material like 10 the usual couch roll in order to best cooperate with the perforated roll 5.

As the web of moist stock passes down between the two rolls, the expressing roll 7 presses it firmly against the perforated 15 surface causing further surplus water therein to pass through the perforations of the cylinder, whence it gravitates through the bottom of the perforated cylinder and into the drip pan 17. The sheet thus formed, as 20 it passes the point of contact between the two rolls, leaves the perforated roll and clings to the couch roll 7, because of the superior adhesive attraction offered by the felt or other surface of the couch roll.

25 It will be observed that the water which is thus expressed through the perforations in the roll 5 not only gravitates in such a direction as to have no contact with the thickened stock, but in draining through 30 the perforations in the lower half of the perforated cylinder tends to wash these perforations free from the accumulated fibre and maintain the roll clean and effective for the draining action.

35 The stock having been preliminarily drained, is next subjected to a more vigorous expressing action by being subjected to a second pair of rolls, comprising also a perforated cylinder and an expressing roll, 40 these, however, being so constructed as to be capable of exerting a relatively greater pressing action and therefore extracting a substantial amount of the remnant moisture. For this purpose there is provided a 45 second cylinder 33 having a perforated surface adapted to cooperate with an expressing roll 35, the latter however preferably having a smooth, hard, unperforated surface, by means of which a relatively great 50 pressure can be exerted against the perforated roll. In the apparatus shown in Figs. 1 and 2, the web is transferred from the couch or expressing roll 7 to the perforated cylinder 33 by direct contact, the 55 cylinder 33 being constructed to provide a greater adhesive attraction for the web than the couch roll. For this purpose the cylinder 33 is mounted at each end in bearings 37 supported by the arm 39 pivoted at 41 60 to the frame 27. The opposite end of each arm 39 is attached to the link 43 which in turn is jointed to a long weighted arm 45 pivoted at 47 on the base 49 of the machine. The weights 51, which may be adjusted to 65 any required amount, maintain a constant

upward pressure on the perforated roll or cylinder 33 against the couch roll 7, so that the stock delivered by the roll 7 is not only subjected to pressure between the cylinder 33 and the roll 35 but is also subjected to pressure between the cylinder 33 and the roll 7. The stock or web after its delivery to the cylinder 33 passes between the cylinder and the expressing roll 35 and is thereby deprived of further moisture 75 which, like the moisture expressed by the roll 7, drains down into the lower part of the cylinder 33, thence through the perforations in the bottom thereof and into the drip pan or drainage receptacle 53, whence 80 it is withdrawn through the waste pipe 55.

To exert the necessary pressure between the cylinder 33 and the expressing roll 35, the latter is mounted at each end in adjustable bearings 57 slidable horizontally in 85 ways 59 and forced toward the cylinder 33 by relatively heavy springs 61, the pressure of which may be adjusted by the hand-wheel 63 adapted to turn a suitable adjusting screw. The hard, smooth surface of 90 the presser roll 35 acts not only to expel the water from the stock through the perforations in the roll 9, but also to expel air from between the stock and the smooth surface of the roll, so that the fibres tend 95 to cling to the latter rather than to adhere to the perforated surface. The dried fibres, therefore, as they pass the point of contact between the two rolls, leave the perforated cylinder and cling to the smooth roll. 100

In order to withstand the relatively great pressure exerted by the presser roll the perforated cylinder is preferably constructed not only with a foraminous covering, but also of sufficient strength to withstand considerable surface pressure, a construction of this kind, by way of example, being shown in my co-pending application, Serial No. 255,445, filed September 24, 1918, wherein the cylinder is covered with perforated 110 sheet metal, provided with openings which are of lesser diameter than the average length of fibres or slivers to be handled, but reinforced at intervals by radial supports which are carried by a series of spiders, 115 thereby materially stiffening the surface against external pressure. This construction also provides the necessary adhesive construction to cause the web to pass from the couch roll 7 to the cylinder 33, the pressure between the two rolls expelling the excess water which escapes freely through the perforations of the cylinder and causes the fibres to cling to the perforated surface of the latter. 120

The web having passed from the perforated cylinder 33 to the roll 35 is then withdrawn from the smooth roll by any suitable means, as by a doctor blade 65, and may be carried to any other desired appa- 125 130

ratus in the form of a continuous traveling sheet or may be withdrawn and stored for future use.

- The expressing action which is carried out 5 by the pair of expressing rolls 33 and 35 may be repeated in subsequent stages and, by subjecting the sheet to the action of successive pairs of expressing rolls, the extraction of water may be carried on gradually 10 and with the greatest thoroughness. In Fig. 3 I have shown an apparatus similar to that illustrated in Fig. 2, but with the addition of other pairs of expressing rolls which act to further extract moisture from the stock. 15 In Fig. 3 the web, instead of being removed from the expressing roll 35 by a doctor blade, is transferred, as before, directly to the perforated cylinder 67 similar in construction to the cylinder 33, and is subjected 20 to the pressure of the cooperating expressing roll 69 generally similar in construction to the expressing roll 35. This transference of the web from one set of expressing rolls to a succeeding set may be 25 carried out through as many stages as desired, the perforated roll of one set receiving the web directly from the expressing roll of the preceding set either by direct contact therewith or otherwise. In Fig. 3 an 30 additional set of expressing rolls are provided, being embodied in the perforated cylinder 71, also similar to the cylinder 33, and the cooperating expressing roll 73 generally similar to the roll 35, the web being received 35 by the cylinder 71 directly from the expressing roll 69 but with the assistance of the doctor blade 75 which diverts the web from the expressing roll and allows it to pass downward to the perforated cylinder 71 and 40 between the latter and the expressing roll 73. From the roll 73 the web is cleared by the doctor blade 75 and may be delivered, as before, to any desired apparatus or receptacle. 45 The surface of the expressing rolls 35, 69, etc., which is necessary to cause the fibres to cling to the surface of the roll and leave the perforated roll, will depend somewhat on the degree to which moisture has already 50 been extracted from the web. The further the process continues the smoother and harder should be the surface of the roll so as to be more effective in expelling the water between the surface of the roll and the web. 55 Thus, the surface of the first roll 35 should be preferably smooth but not necessarily polished, while the surface of the roll 69 should preferably have a higher finish, and as the successive stages are passed through 60 successive rolls should have a higher polish and should preferably be used under increasing pressure.

While I have herein shown for the purpose of illustration one specific embodiment 65 of the invention, it is to be understood that

the same is not limited to specific details herein shown nor to the form or relative arrangement of parts, but that extensive deviations may be made therefrom without departing from the spirit thereof.

70

Claims:

1. The process of extracting moisture from paper stock which consists in applying the stock from above to a foraminous cylindrical surface, withdrawing surplus moisture by gravity through the walls of the cylinder, transferring the stock from the cylinder to a couch roll and therefrom to a second foraminous cylinder, the latter capable of withstanding relatively greater 75 pressure, and subjecting it thereafter to the relatively greater pressure of a cooperating expressing roll.

2. The process of extracting moisture from paper stock which consists in applying the stock from above to a foraminous cylindrical surface, withdrawing surplus moisture by gravity through the walls of the cylinder, subjecting the drained stock to the pressure of a cooperating roll, and thereafter causing it to travel upon the surface of a second foraminous cylinder and subjecting it to further and greater pressure to extract further moisture.

3. The process of forming a web from paper stock which consists in dropping a uniform stream of stock on a foraminous cylindrical surface, withdrawing surplus moisture by gravity through the walls of the cylinder, subjecting it to the pressure 100 of a couch roll, transferring the sheet to a second perforated cylinder capable of withstanding considerable pressure, and subjecting the sheet thereon to relatively greater pressure by the action of a second expressing roll.

4. The process of forming a web from paper stock which consists in dropping a uniform measured stream of stock on a foraminous cylindrical surface, withdrawing 110 surplus moisture by gravity through the walls of the cylinder, and subjecting the sheet to a plurality of expressing actions while in direct contact with a foraminous surface to extract further moisture.

5. The process of extracting moisture from paper stock which consists in applying it from above to a foraminous cylindrical surface, withdrawing surplus moisture by gravity through the walls of the cylinder, subjecting it to the action of an expressing roll, and thereafter subjecting it to further squeezing action while in direct contact with the squeezing agencies.

6. The process of forming a web from paper stock which consists in dropping a uniform measured stream of stock on a foraminous cylindrical surface, subjecting the sheet to the pressure of a cooperating roll, conveying the sheet to a second perforated 125

130

- rated cylinder, and subjecting it to a second expressing operation by the action of a second expressing roll.
7. The process of forming a web from paper stock which consists in dropping a uniform measured stream of stock on a foraminous cylindrical surface, withdrawing surplus moisture by gravity through the walls of the cylinder, subjecting the sheet to the pressure of a cooperating pressure roll and thereafter causing it to travel between and in direct contact with the surfaces of one or more pair of presser rolls.
8. The process of forming a web from paper stock which consists in dropping a uniform measured stream of stock on a foraminous cylindrical surface, withdrawing surplus moisture by gravity through the walls of the cylinder, subjecting it to the pressure of a cooperating roll, transferring it by direct contact to a second perforated roll, and subjecting it thereon to the action of a second expressing roll.
9. The process of forming a web from paper stock which consists in dropping a uniform stream of stock on a foraminous cylindrical surface, withdrawing surplus moisture by gravity through the walls of the cylinder, draining the same through the bottom of the cylinder, and subjecting the sheet to the pressure of a cooperating expressing roll.
10. The process of removing moisture from paper stock which consists in causing the stock to gravitate between the surface of a foraminous cylinder and a couch roll and expressing water thereat, transferring the thickened stock to a second perforated cylinder and expressing further moisture therefrom.
11. In an apparatus for removing moisture from paper stock, the combination with the cylinder 5, the stock supply 9 adapted to drop the stock on the cylinder, the couch roll 7, a second perforated cylinder 33, and expressing roll 35.
12. In a paper making apparatus for removing the water from paper stock, the combination with a perforated cylinder of means for applying moist stock to the cylinder from above, a cooperating roll, said cylinder roll being so related as to permit the presentation between them of stock from which water is to be expressed, the roll and cylinder being pressed toward each other to express water from the stock and cause it to pass through the perforations in the surface, a second perforated cylinder adapted to receive the stock, and a cooperating pressure roll related to said second cylinder.
13. In a machine for forming a web of paper stock, the combination with a foraminous cylinder of means for dropping a measured stream of stock from above on the cylinder to form a web, a couch roll, means for
- pressing the same toward the cylinder with a relatively gentle pressure, a second foraminous cylinder capable of withstanding relatively greater pressure, a smooth expressing roll cooperatively related to said second cylinder, and means for pressing the same toward said second cylinder with relatively greater pressure, the web being adapted to pass from the couch roll to said second cylinder.
14. In a machine for extracting moisture from paper stock, the combination with a foraminous cylinder of means for applying the stock from above on the cylinder, means to drain away surplus moisture through the cylinder walls, a couch roll, a second foraminous cylinder to receive the web, a smooth expressing roll pressed toward said second cylinder, a doctor blade to remove the stock from said expressing roll, a third perforated cylinder to receive the stock removed by the doctor blade, and an expressing roll cooperating therewith.
15. In a machine for forming a web of paper stock having a foraminous cylinder, means for dropping a measured stream of stock from above on the cylinder to form a web, means to drain away surplus moisture through the perforations in the lower part of the cylinder, a couch roll adapted to press against the sheet formed on the cylinder, a second foraminous cylinder adapted to receive the sheet formed on the first cylinder, and an expressing roll engaging the sheet on said second cylinder.
16. In a web forming machine for paper stock, the combination with a foraminous cylinder of means for dropping a measured stream of stock from above on the cylinder to form a web, means to drain away surplus moisture through the cylinder walls, a couch roll adapted to press against the sheet formed on the cylinder, a second foraminous cylinder adapted to receive the sheet from the couch roll by direct contact therewith, and an expressing roll cooperatively related to said second cylinder.
17. In a machine for expressing moisture from paper stock, a foraminous cylinder, means for applying stock to the cylinder from above, means to drain away surplus moisture through the cylinder walls, an expressing roll engaging the stock on the cylinder and adapted to receive the thickened stock therefrom, a second foraminous cylinder in contact with the stock on said expressing roll to take the stock therefrom, and a second expressing roll engaging the stock on said second cylinder.
18. In a machine for extracting moisture from paper stock, the combination with a foraminous cylinder of means for applying the stock thereto from above, means to drain away surplus moisture through the cylinder walls, a roll subjecting the stock on the cylin-

- der to an expressing action, and means to withdraw the stock from the roll to the surface of a second foraminous cylinder and subject it to a relatively greater pressure 5 for extracting further moisture therefrom.
19. In a web forming machine for paper stock, the combination with a foraminous cylinder of a couch roll, means for dropping a measured stream of stock from above on 10 the cylinder to form a web, and means to receive the web from the couch roll and express further moisture therefrom, the same comprising a second perforated cylinder capable of withstanding greater pressure 15 than the first cylinder, and a smooth expressing roll pressed into cooperative relation to the second cylinder.
20. In a machine for extracting moisture from paper stock, the combination of a foraminous cylinder and co-operating expressing roll, a doctor blade to remove stock from said roll, a second foraminous cylinder to receive the stock removed by said doctor 20
- blade, and an expressing roll cooperating with said second cylinder. 25
21. In a web forming machine for paper stock, the combination with a foraminous cylinder of means for dropping a measured stream of stock from above on the cylinder to form a web, means to drain away the surplus moisture through the cylinder walls, and means for pressing the sheet against the cylinder to express further moisture therefrom. 30
22. In a web forming machine for paper stock, the combination with a foraminous cylinder of a couch roll, means for dropping a measured stream of stock from above on the cylinder to form a web, and means to receive the web from the couch roll and express 35 further moisture therefrom, comprising a second perforated cylinder and an expressing roll co-operating therewith. 40

In testimony whereof, I have signed my name to this specification,

ANTON J. HAUG.
